UNITED STATES PATENT OFFICE.

IVA BELLE KEMPSHALL, OF BOSTON, MASSACHUSETTS.

DESIGN FOR AN AUTOMOBILE-TIRE.

40,586.

Specification for Design.

Patented Mar. 22, 1910.

Application filed January 21, 1910. Serial No. 539,434. Term of patent 14 years.

To all whom it may concern:

Be it known that I, IVA BELLE KEMPSHALL, a citizen of the United States, residing at Boston, in the county of Suffolk and State of Massachusetts, have invented a new, original, and ornamental Design for Automobile-Tires, of which the following is a specification, reference being had to the accompanying drawing, forming part thereof.

Figure 1 is a plan view of a portion of the

tread of an automobile tire, showing my new design. Fig. 2 is a side view of the same.

I claim:

The ornamental design for an automobile tire, as shown.

IV A BELLE KEMPSHALL.
